TOY SAVINGS BANK OR SIMILAR ARTICLE

Alettha S. Evans, Bergenfield, N.J.

Application December 10, 1957, Serial No. 48,858

Term of patent 14 years

(Cl. D34—11)

The single figure is a perspective view of a toy savings bank or similar article, showing my new design.

The opposite side of the bank, not shown, is substantially a mirror image of the side shown, and the rear, not shown, is conventional. The broken-line showing of legible matter in the drawing is for illustrative purposes only.

I claim:

The ornamental design for a toy savings bank or similar article, as shown and described.
